Primary Examiner — Mark Goodwin(74) *Attorney, Agent, or Firm* — Saidman DesignLaw Group, LLC(57) **CLAIM**

the ornamental design for a track link assembly, as shown and described.

DESCRIPTION

FIG. 1 is a perspective view of a track link assembly showing our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The uniform dashed broken lines illustrate structure or features that form no part of the claimed design.

The relatively thin shade lines represent contour, not surface ornamentation.
